RECORD ELEMENT HOLDER

Forest L. W. Link, Silverton, Ohio, assignor to
The Globe-Wernicke Company, Norwood, Ohio,
a corporation of Ohio

Application March 13, 1939, Serial No. 261,435

6 Claims. (Cl. 129—16.7)

This invention relates to visible index systems and particularly to card holders therefor. The advantages of the visible index type of system are well known and need not be pointed out in detail here. Generally speaking a visible index file is one in which a number of holders are carried in a shallow drawer, each of said holders carrying one or more pockets for carrying record cards or each of the holders carrying directly the record cards whereby the cards may be substantially flat in said drawer in overlapped relation, and whereby any desired number may be turned over so that an individual card may be examined in detail.

Visible index systems now on the market are generally quite expensive and are thus not available to a large number of potential users. It is an object of my invention, therefore, to provide a holder for a visible index system which will be extremely simple and very inexpensive to manufacture whereby the cost of the system may be brought down to a level to make it available to the small businesses which have heretofore not been able to obtain the advantages thereof.

It is a further object of my invention to provide a holder of such nature that record cards or pockets for carrying the record cards may be expeditiously inserted and removed from the holder by a simple manual procedure without the necessity of operating any fastening element or the like, and which will nevertheless hold the cards in position so that they will not be removable from the holder except by a positive act.

These and other objects of my invention which are to be described hereinafter or which will be apparent to one skilled in the art upon reading these specifications, I accomplish by that certain construction and arrangement of parts of which I shall now describe exemplary embodiments.

Reference is now made to the drawing which forms a part hereof, and in which:

Figure 1 is a plan view of the blank from which a holder according to my invention is formed.

Fig. 2 is an end elevation thereof.

Fig. 3 is a plan view of the completely formed holder.

Fig. 4 is an end elevation of Fig. 3.

Fig. 5 is a side elevation of a holder showing a card in position to be placed in the holder.

Fig. 6 is a cross sectional view on an enlarged scale taken on the line 6—6 of Fig. 5.

Fig. 7 is a view similar to Fig. 6 showing the card during the inserting operation.

Fig. 8 is a view similar to Figs. 6 and 7 showing the card in position.

Fig. 9 is a view similar to Figs. 6, 7 and 8, showing the position of the card at a stage in the procedure for removing the card from the holder.

Fig. 10 is an elevational view of Fig. 9 looking from the left in that figure and with parts broken away.

Fig. 11 is a perspective view of an exemplary tray containing a number of holders according to my invention, and a follower block for holding the card holders in place.

Fig. 12 is a cross sectional view similar to Fig. 6 of a modified form of my invention.

Briefly, in the practice of my invention, I provide a generally comb shaped blank comprising a substantially strip like portion 10 having a plurality of teeth extending therefrom, as indicated at 11. As shown in the figure these teeth are preferably rounded at their ends. In forming up the holder the strip like portion 10 is formed into a generally channel like configuration and the teeth 11 are bent over in an arcuate shape so that the ends of the teeth 11 extend below the opposite edge of the channel shaped portion. Referring to Fig. 4, it will be noted that the forming operation is such that it forms a right angle at 12 and right angles 13 at each end only of the opposite side and that intermediate the right angle portions 13 the opposite side of the channel like portion is arcuately curved as indicated at 14 in the various figures. The reason for this is that the curvature 14 is desirable in my invention, as will be pointed out hereinafter, and yet in order that the holder may have a solid seat in its tray, it is desirable that the end portion thereof be flat. As will be seen in the various figures, the ends of the holder are provided with the flat portions 13a while the central portion therebetween is curved on one side.

The holders will preferably be held in a tray 15 of conventional structure having the downturned edge portions 16. The end portions of the holder engage underneath the flanges 16 and a plurality of the holders are held in position by means of a follower block 17, which may be of any desired type and will preferably be of the type disclosed in my Patent No. 2,178,638, dated Nov. 7, 1939. When it is desired to remove a holder or add a holder to the drawer, the follower block 17 is retracted and the individual holders may then be skewed diagonally, thus removing their end portions from engagement under the flanges 16.

As pointed out above, a holder according to my invention may be used in connection with a

pocket, said pocket being adapted to carry one or more record cards, for example, as disclosed in my said patent, or the holder may be used directly with a record card. In this case I will 5 describe its use in connection with a record card 18, but it will be understood that this description applies equally to a pocket for record cards and the use of the term "record element" in the claims is intended to cover both a record element 10 per se and a pocket for carrying record elements.

The card 18, as shown in Fig. 5, is provided with a number of rectangular perforations 19 which are spaced in the same manner as the teeth 11 of the holder. The perforations 19 are 15 disposed adjacent the lower edge of the card and the card itself as seen in the figure, is slightly narrower at its lower end by virtue of the cutouts 20 which clear the end portions 13a of the holder.

20 The card is preferably made from a relatively stiff material so that when its lower edge (as seen in the drawing) is curved or deformed as hereinafter described, it will readily snap back into flat condition.

25 The card is inserted in the following manner: It is lowered into the holder in the position shown in Figs. 5 and 6 in the direction of the arrow. It will be noted that in the forming of the holder the ends of the teeth 11 have been bent short of 30 the opposed portion of the channel so as to leave a space indicated in Fig. 6 at 21. The lower edge of the card is slipped into this space and, as shown in Fig. 7, the card will be bent by virtue of the curvature 14 until the perforations 19 of 35 the card reach the ends of the teeth 11. At this point the resiliency of the card will cause it to tend to straighten, (the card being indicated at a transitory position in dotted lines at 22) until the card attains the position shown in dotted lines 40 at 23. As shown in Fig. 8, the card may now lie flat and may be turned over without disengagement from the teeth 11 since the ends of the teeth 11 project below the edge 10a of the holder.

The procedure in removing a card from the 45 holder is as follows: Referring to Figs. 9 and 10, the card is first pushed downwardly whereby the upper edge of the perforations 19 is brought below the ends of the teeth 11, whereby the teeth are withdrawn from engagement in the perforations. The card is then simply moved sideways 50 as shown in Fig. 10, until the perforations 19 come between the teeth 11. The card may then readily be withdrawn.

It will be seen that I have provided a very 55 inexpensive and simple card holder for a visible index system, said holder being made of a single piece of material and having no moving parts. Yet as has been pointed out, a card may be inserted in the holder by a single motion and may 60 be removed from the holder by a combination of three simple movements (downwardly, laterally and upwardly).

In accordance with the modification of my invention shown in Fig. 12, the entire length of the 65 holder has a channel shaped cross section similar to that at the ends of the preferred form heretofore described at 13a. I have found that a card may be inserted and removed from this type of holder in a manner similar to that described 70 above, and of course this construction is still cheaper.

It will of course be clear that modifications 75 may be made in my invention without departing from the spirit thereof and that the precise configuration of the parts may be varied, and I there-

fore wish it to be understood that I do not intend to limit myself otherwise than as pointed out in the claims which follow.

Having now fully described my invention, what I claim as new and desire to secure by Letters 5 Patent, is:

1. A visible index card holder comprising a generally channel shaped element, the shape of said element being modified intermediate the ends thereof, so that one arm of said channel extends 10 upwardly from the web in a smooth curve and a plurality of teeth extending upwardly, inwardly and downwardly from the other arm of said channel in an arc, the ends of said teeth extending slightly below the upper edge of the opposed arm 15 of said channel.

2. A visible index card holder comprising a generally channel shaped element, the shape of said element being modified intermediate the ends thereof, so that one arm of said channel extends 20 upwardly from the web in a smooth curve and a plurality of teeth extending upwardly, inwardly and downwardly from the other arm of said channel in an arc, the ends of said teeth extending slightly below the upper edge of the opposed arm 25 of said channel, said channel and teeth being made from a non-resilient material.

3. A card holder for visible index systems comprising a generally channel shaped element, said element intermediate its ends being formed with 30 an arcuate side and a substantially vertical side, and having a plurality of teeth extending in an arc upwardly, inwardly and downwardly from said substantially vertical side, the ends of said teeth extending slightly below the upper edge of said 35 arcuate side and being inwardly spaced therefrom.

4. A card holder for visible index systems comprising a generally channel shaped element, said element intermediate its ends being formed with 40 an arcuate side and a substantially vertical side, and having a plurality of teeth extending in an arc upwardly, inwardly and downwardly from said substantially vertical side, the ends of said teeth extending slightly below the upper edge of said arcuate side and being inwardly spaced therefrom, said holder being integrally formed from a 45 non-resilient material.

5. In combination with a card holder according to claim 3, a record element made from a 50 relatively stiff material and having a number of generally rectangular perforations along its lower edge spaced to mate with the teeth on said holder whereby said record element may be engaged with said holder by being inserted between said arcuate portion and said teeth and 55 thrust downwardly, and whereby the stiffness of the material of the record element will cause the same to straighten and the perforations to engage with the teeth when the lower edges of said perforations pass the edges of said teeth, 60 and whereby said record element may be removed from said holder by being thrust further downwardly until the upper edges of said perforations pass the edges of said teeth and then being moved laterally and withdrawn. 65

6. A card holder for visible index systems comprising a generally channel shaped element, said element having an arcuate side and a substantially vertical side, and having a plurality of teeth extending in an arc upwardly, inwardly 70 and downwardly from said substantially vertical side, the ends of said teeth extending slightly below the top edge of said arcuate side and being inwardly spaced therefrom.
